UNITED STATES PATENT OFFICE.

ANTHONY A. ELMETT, OF NEW YORK, N. Y.

COMB.

Application filed October 15, 1926. Serial No. 141,718.

This invention relates to combs in general, and more especially to combs having removable teeth.

Among the objects of the present invention it is aimed to provide a comb, the teeth of which can be readily separated from one another to facilitate cleaning the same.

Another object of the invention is to provide a comb having a supporting frame and plurality of teeth removably attached thereto, so that when any of the teeth become bent or broken, they can easily be removed and repaired or replaced by new teeth. This feature is of particular advantage with combs having expensive frame members composed of precious metals and the like, especially when such combs form cherished gifts, the life of which it is desired to extend as long as possible.

Among other objects of the present invention it is aimed to provide a construction of comb, the several parts of which may be composed of metal produced at low cost so that they can be retailed at a comparatively low price.

It is a still further object of the present invention to provide a comb in which a greater or less number of teeth may be provided with a given length of frame, so that the length of handle with a given length of frame may be regulated by the user to suit his preference.

These and other features, capabilities and advantages of the invention will appear from the subjoined detail description of one specific embodiment thereof illustrated in the accompanying drawings, in which

Figure 1 is a side elevation of a comb made according to the present invention with a portion thereof broken away.

Fig. 2 is an end view looking at Fig. 1 from the right, with the anchoring screw removed.

Fig. 3 is an enlarged fragmental side elevation of the comb partly in section.

Fig. 4 is a section on the line 4—4 of Fig. 3.

In the embodiment illustrated, there is provided a frame member 1 which may be composed of any suitable material such as metal, rubber composition, celluloid or the like, and form the outer handle to be grasped by the user. It is also intended that this frame portion 1 may be composed of precious metal such as silver, gold and the like, for expensive toilet sets, when the same would preferably be decorated in the well

known manner, or else that this frame portion 1 be used as the support for the envelope of decorated precious metal or the like.

The frame member 1, as shown in Fig. 4, is somewhat U-shaped, having an elongated shallow recess 2 extending its full length, such recess 2 continuing into the larger round recess 3 and terminating in the diminished mouth 4, preferably narrower than the diameter of the recess 3, the sides of which mouth 4 are preferably plane and parallel.

One end of the frame 1 is provided with an annular recess 5 surrounding the recess 3, and the peripheral wall of the recess 3, for a short extent inwardly from such recess 5, is internally screw threaded, as shown at 6.

At the other end of the frame 1, there is provided a tooth-shaped end piece 7 which is preferably riveted in place by the rivet 8. The end piece 7 has an outer curved edge 9 conforming with the curved end 10 of the frame 1, has a broad flat tooth portion 11, and an enlarged curved portion 12, the tooth portion 11 and the curved portion 12 being spaced from one another by the diminished neck portion 13. The sides of the recess 4 cooperate with the neck 13 to anchor the end piece 7 against radial displacement relative to the frame member 1, and the curved portion 12 cooperates with the recess 3 to anchor the end piece 7 against lateral displacement relative to the frame member 1, and the rivet 8 positively anchors the end piece 7, particularly anchoring the end piece 7 against longitudinal displacement relative to said frame member 1.

The teeth 14, the number of which will be determined according to the length of comb desired, each have a curved enlargement 15 conforming to the recess 3 and cooperating therewith to anchor the teeth against lateral displacement relative to the frame member 1. Each tooth 14 also is provided with a neck portion 16 adjacent to the curved enlargement 15 and terminates in a tooth proper 17 which is tapering, having its broadest portion adjacent to the neck portion 16, as illustrated in Figs. 2 and 4. The teeth proper 17 are spaced from one another as clearly shown in Figs. 1 and 3, the neck portion 16 being considerably wider than the teeth proper 17. This separation idea is carried out in the end piece 7 which is recessed at 18 so that its neck portion 13

projects laterally beyond the flat portion 11, as indicated in Fig. 3, to engage the neck portion 16 of the adjacent tooth member 14.

When assembling the device, the end piece 7 is first secured in place by sliding its enlarged portion 12 and neck portion 13 into the recesses 3 and 4 until the portion 7 is located at the left hand end of the frame member 1, whereupon the rivet 8 is screwed in place to anchor such end member against displacement.

Thereupon, the teeth 14 are successively positioned by sliding their enlargements 15 and neck portions 16 along the recesses 3 and 4 until the desired number of teeth 14 have been mounted on the frame 1.

To anchor the teeth members 14 against longitudinal displacement, any suitable fastening means may be provided. In the present instance a screw 19 of desired length is then threaded through the threaded portion 6 until its end 20 securely anchors the teeth 14 in place against the end piece 7. The screw 19 may be of any suitable form or shape. In the present instance it is provided with a knurled head 21 by means of which the same may be conveniently grasped.

When any of the teeth become bent or broken, it is only necessary to remove the screw 19 when the teeth 14 will be free to be removed and the broken or bent teeth replaced. Similarly, when it is desired to clean the teeth 14, the screw 19 will be removed and the teeth 14 can then be washed and wiped as desired and again returned into position in the frame 1.

The recess 2 is of particular value in this construction in that it affords a certain amount of yieldability to the walls of the recesses 3 and 4 to facilitate adjusting the frame member 1 to the head portions 15 of the teeth 14.

It is obvious that various changes and modifications may be made to the details of construction without departing from the general spirit of the invention as set forth in the appended claims.

I claim:

1. A comb having a frame provided with a fixed tooth forming a fixed end piece, there being in said frame a longitudinal slot having an enlarged inner longitudinal recess extending from said end piece to the other end of said frame, said other end of the frame being internally threaded, a plurality

of teeth having enlarged heads, the enlarged heads of said teeth being slipped into place in said enlarged recess by entering through the internally threaded end of said frame with the teeth shanks projecting through said longitudinal slot, and a screw engaging said internally threaded end of said enlarged recess and abutting against the outermost tooth head and operable to urge said tooth heads against one another and against said end piece.

2. A comb having a frame provided with a longitudinal slot having an enlarged inner longitudinal recess, there being a longitudinal narrow recess in said frame extending inwardly from the wall of said enlarged recess, and a plurality of teeth having enlarged heads, the enlarged heads being disposed in said enlarged recess, the narrow recess permitting the walls of said frame yieldably to engage the head portions of said teeth.

3. A comb having a frame member provided with a longitudinal slot having an enlarged inner longitudinal recess; an end piece extending into said slot at one end of said frame member, the other end of said enlarged recess being internally threaded; a plurality of teeth having enlarged heads, the enlarged heads being disposed in said enlarged recess; and a screw engaging the threaded end of said enlarged recess and cooperating to anchor said teeth adjacent to one another and against said end piece, said end piece being riveted to said frame member.

4. A comb having a frame member provided with a longitudinal slot having an enlarged inner longitudinal recess; an end piece extending into said slot at one end of said frame member, the other end of said enlarged recess being internally threaded; a plurality of teeth having enlarged heads, the enlarged heads being disposed in said enlarged recess; and a screw engaging the threaded end of said enlarged recess and cooperating to anchor said teeth adjacent to one another and against said end piece, there being a longitudinal narrow recess in said frame member extending inwardly from the wall of said enlarged recess to permit the walls of said frame member yieldably to engage the head portions of said teeth.

ANTHONY A. ELNETT.
